CLAIM

The ornamental design for a sliding actuator for a window shade cord protector, as shown and described.

DESCRIPTION

FIG. 1 is a perspective view of a sliding actuator for a window shade cord protector.

FIG. 2 is a left side elevation view of a sliding actuator for a window shade cord protector.

FIG. 3 is a right side elevation view of a sliding actuator for a window shade cord protector.

FIG. 4 is a rear elevation of a sliding actuator for a window shade cord protector.

FIG. 5 is a front elevation view of a sliding actuator for a window shade cord protector.

FIG. 6 is a top plan view of a sliding actuator for a window shade cord protector; and,

FIG. 7 is a bottom view of a sliding actuator for a window shade cord protector.

The dashed lines shown depict the environment and represent unclaimed subject matter and form no part of the claimed design.

1 Claim, 5 Drawing Sheets
